UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF NEW JERSEY.

CYLINDER PRINTING-MACHINE.

1,089,740.

Specification of Letters Patent.

Patented Mar. 10, 1914.

Application filed September 16, 1909. Serial No. 518,003.

To all whom it may concern:

Be it known that I, HOWARD M. BARBER, a citizen of the United States, and resident of Stonington, in the county of New London 5 and State of Connecticut, have invented new and useful Improvements in Cylinder Printing-Machines, of which the following is a specification.

This invention relates to improvements in 10 cylinder printing machines and has for its object to provide novel means for raising and lowering the impression cylinder whereby the impression cylinder may be held rigidly under any printing strain and thereby 15 by improve the quality of work produced by the press.

My invention further consists in certain 20 improvements in the construction, form and arrangement of the several parts of the mechanism for raising and lowering the impression cylinder whereby the objects above set forth may be accomplished by a very simple and effective mechanism.

My invention is herein shown and described in connection with a two-revolution 25 rotary cylinder printing machine but it is applied to cylinder printing machines of other forms with equal facility and without departing from the spirit and scope of 30 the invention.

In the accompanying drawings, Figure 1 represents in side elevation a portion of a two-revolution rotary cylinder printing machine, with my invention applied thereto, 35 Fig. 2 is a longitudinal vertical section through the same taken adjacent to one of the side frames, Fig. 3 is a detail longitudinal vertical section showing the impression cylinder and portions of the form cylinder, 40 the feeding table and the stripping fingers of the sheet delivery mechanism, Fig. 4 is a detail horizontal section showing the rotary cam and its adjacent parts, Fig. 5 is a section taken in the plane of the line A—A of 45 Fig. 4 looking in the direction of the arrows, Fig. 6 is a detail section through one of the impression cylinder shaft journal boxes and its adjacent parts, and Fig. 7 is a section taken in the plane of the line B—B of Fig. 50 6, through both of the impression cylinder shaft journal boxes.

The side frames of the machine are denoted by 1 and the usual feeding table by 2. The impression cylinder 3 is provided with the usual grippers 4 arranged to take the 55 sheets to be printed from the feed table 2 and transfer them to the delivery mechanism. The usual stripping fingers of the delivery mechanism are denoted by 5 and are arranged to strip the sheets from the impression cylinder. 60

The form cylinder is denoted by 6. The impression and form cylinder shafts are denoted by 7 and 8 respectively and their journal boxes by 9 and 10. The boxes 10 for the 65 form cylinder shaft 8 are mounted stationary in the side frames 1 of the machine and the journal boxes 9 for the shaft 7 of the impression cylinder are slidably mounted in the said side frames 1. 70

The means for raising and depressing the impression cylinder are as follows:—A rock shaft 11 is mounted in suitable bearings in the side frames 1, which shaft has fixed thereto arms 12, 13. Rock shafts 14, 15, are 75 mounted in caps 16, 17, over the journal boxes 9, which shafts are provided with cams for forcing the boxes 9 and thereby the cylinder 3 toward the form cylinder 6. In the present instance, these cams are 80 shown as eccentrics 18, 19, provided with rollers 20, 21. Adjustable gibs 22 are interposed between the rollers 20, 21, and the impression cylinder shaft boxes 9 for accurately adjusting the position of the boxes 85 with respect to the eccentric cams 18, 19. These gibs 22 are adjusted by any suitable means, such, for instance, as providing for each gib a screw 23 secured to the box 9; an adjusting nut 24 on the screw engaging the gib 90 and a lock nut 25 also on the screw for locking the adjusting nut 24 in position. The rock shafts 14, 15, are provided with arms 26, 27; fixed thereto and the free ends of these arms 26, 27, are connected to the 95 free ends of the arms 12, 13, of the rock shaft 11 by rods 28, 29.

The rotary cam shaft 30 is provided with a box cam 31, the groove 32 of which is adapted to receive a roller 33 of a cam slide 34. 100 Embracing the shaft 30. This slide is supported at its end opposite the roller 33 by

providing the slide with an elongated slot 35 through which extends the pin 36 of the gab hook arm 37 fixed to the rock shaft 11. The cam slide 34 is also slidably mounted 5 upon the cam shaft 36. A gab hook 38 is pivoted at 39 on the slide 34, which hook removably engages the pin 36 on the gab hook arm 37 for rocking the arm and thereby the shaft 11 as the cam slide 34 is moved 10 back and forth by the rotary movement of the cam 31.

Manually controlled means are provided for disconnecting the gab hook 38 from the arm 37 at pleasure, as follows: A rock shaft 15 40 is mounted in one of the side frames 1, which rock shaft has fixed thereto oppositely extended arms, 41, 42. The arm 41 is provided with a laterally extended lug 43 located beneath the weighted extension 44 20 of the gab hook 38. The arm 42 is provided with an uprising arm 45 projecting through the floor or platform 46 and provided with a foot piece 47. The depression of this foot piece 47 will raise the arm 41 and thereby 25 lift the gab hook 38 out of engagement with the pin 36 of the arm 37.

The impression cylinder 3 is yieldingly held at the limit of its upward movement away from the form cylinder 6 by spring 30 means of the required pressure. In the present instance, two pairs of springs 48, 49, are interposed between shoulders 50 on the side frames 1 and adjusting nuts 51 on the screw threaded portions of pins 52, the heads 35 of which pins bear against the under sides of the boxes 9 and the shafts of which pins are guided in the side frames 1.

In operation, in the accompanying drawings, the impression cylinder is shown in 40 its raised position under the influence of the lifting springs 48, 49, with its grippers closed upon a sheet fed from the feeding table 2. After the impression cylinder grippers have seized the advance edge of the 45 sheet, the rotary movement of the cam 31 will bring its groove 32 in position to start the cam slide 34 on its inward movement. Because of the connection between the gab hook 38 and the arm 37 this inward movement of the cam slide 34 will rock the arm 37 and thereby the rock shaft 11 in a direction to swing the arms 12, 13, and thereby 50 the arms 26, 27, downwardly thus causing the eccentric cams 18, 19, to force the boxes 55 9 of the impression cylinder shaft 7 downwardly for bringing the form and impression cylinders into printing contact just before the sheet is brought by the grippers on the impression cylinder into position for receiving its printing impression. The cam groove 32 is so shaped that after the rear end of the sheet has passed the printing point, the rock shaft 11 will be moved back 60

to its original position thus permitting the lifting springs 48, 49, to exert their pressure 65 to lift the impression cylinder away from the form cylinder. This is accomplished before the grippers come for a second time to the point of contact between the form and impression cylinders so that during the 70 second revolution of the impression cylinder while the printing sheet is being taken off by the delivery mechanism, the impression cylinder will be lifted away from the form cylinder and held in such position by the 75 lifting springs.

If, for any reason, after a sheet has been seized by the grippers, it is desired to prevent the sheet from receiving an impression, the operator may prevent the depression of 80 the impression cylinder by lifting the gab hook 38 out of its engagement with the arm 37, through the depression of the foot piece 47, thus disconnecting the cam slide from the rock shaft 11. 85

The weighted extension 44 of the gab hook 38 will cause the gab hook when released to fall by gravity into engagement with the pin 36 on the arm 37.

The gibs 22 carried by the journal boxes 90 9 may be adjusted for changing the impression pressure or lifting pressure and furthermore the nuts 51 may be adjusted for changing the lifting pressure.

By the use of the mechanism constructed, 95 arranged and operated, as herein set forth, it will be seen that the lifting pressure is applied directly to the impression cylinder shaft journal boxes and that also the means for forcing the cylinder downwardly is also 100 applied directly to the said journal boxes thus doing away with intermediate parts and also insuring an absolutely rigid support for the impression cylinder during its printing operation. It will, furthermore, 105 be seen that a very simple arrangement is provided for disconnecting the cam from the impression cylinder operating means when so desired. 110

What I claim is:—

1. An impression cylinder, its journal boxes, their lifting springs, depressing cams and means for automatically operating the depressing cams at predetermined intervals comprising cam shafts, their arms, a rock 115 shaft, its arms, rods connecting the corresponding arms of said shafts, a rotary cam, its slide, a gab hook carried thereby and gab hook arms carried by the rock shaft and engaged by said gab hook. 120

2. An impression cylinder, its journal boxes, their lifting springs, depressing cams and means for automatically operating the depressing cams at predetermined intervals comprising cam shafts, their arms, a rock 125 shaft, its arms, rods connecting the corre-

sponding arms of said shafts, a rotary cam, its slide, a gab hook carried thereby, gab hook arms carried by the rock shaft and engaged by said gab hook, and a manually controlled device for disconnecting the gab hook and gab hook arm at pleasure.

5 In testimony that I claim the foregoing

as my invention, I have signed my name in presence of two witnesses, this fourteenth day of September A. D. 1909.

HOWARD M. BARBER.
